UNITED STATES PATENT OFFICE

DARWIN M. HESTON, OF PRINCETON, INDIANA

PORTABLE PRESSURE DISPENSING SYSTEM

Application filed December 26, 1929. Serial No. 416,552.

This invention relates to a portable pressure dispensing system.

The chief object of this invention is to provide a readily detachable fixture, adapted to be associated with the bung hole of a liquid or semi-liquid container for rapid dispensing of the container contents.

One feature of the invention consists in the provision of a pressure supply associated with the bung fitting.

A second feature of the invention consists in the combination of a relatively rigid discharge connected to a relatively flexible supply line through the instrumentality of a bung receivable fixture.

The full nature of the invention will be understood from the accompanying drawings and the following description and claim.

20 In the drawings, Fig. 1 is a central sectional view of a container, mounted for portability and with the invention shown in elevation and applied thereto. Fig. 2 is an enlarged central sectional view of the bung fitting and parts carried thereby, a portion being shown in elevation and another portion being broken away.

In the drawings 10 indicates a container including a top or head 11 and a bottom 12. 30 The top 11 is provided with the bung opening, defined by a collar construction 13 having a central opening therethrough and internally threaded for receiving a plug closure having an exposed tool engageable portion which is normally mounted therein after the container has been filled with the liquid to be dispensed. Herein the liquid is indicated by the numeral 14 and the level thereof is that when the majority of the liquid has 40 been discharged from the container 10. The container may be mounted upon a truck or similar device 15 for portability if desired. The truck need not however, be provided, although it facilitates the movement of the container to the vicinity of the high pressure air supply such as commonly provided at filling stations remote from the dispensing portion of the station.

45 A faucet 16 including the control and regulating handle 17 has threaded connection

with the discharge line 18. Discharge line 18 has threaded connection with the upper end of the bung receivable fixture 19 the same including a central tubular portion 20 of greater cross sectional area than line 18. 55

A flexible conduit 21 extends upwardly through said tubular portion 20 and herein is shown suitably connected to conduit 18 preferably by a fluid tight connection. Flexible conduit 21 is shown as of slightly less diameter 60 than conduit 18. Conduit 21 extends into conduit 18 and a solder connection or joint 22 seals the same. The flexible conduit 21 terminates in an open fitting which may be simply that of a coupling 23. Mounted 65 therein may be a suitable screen construction if desired or the same may be omitted. The conduit 21 is of a sufficient length to permit intake 23 to rest upon the bottom of the container. 70

The fixture 19 in addition to including the central tubular chamber 20, includes an intermediate tool engageable portion 25 herein shown hexagonal and the opposite end of fixture 19 includes an externally threaded skirt 26 receivable by the internally threaded portion 13 defining the bung opening and from which the usual plug has been previously removed. 75

Suitably supported by the fixture 19 in the threaded lateral opening 30 is an externally threaded member 31 having the passage 32 therein and provided with a tool engageable portion 33, whereby the same may be readily mounted in said threaded opening. Supported by the member 31 is an air valve casing 34, which detachably supports, as by threaded engagement or the like, a cap construction 31. Mounted within the air valve casing 34 is the usual air construction such as 80 commonly employed in bicycle tires and automobile tires.

The operation of the device is as follows:—

85 Cap 35 is removed and the air chuck of a high pressure air supply hose is applied to the exposed end of air valve casing 34. The air pressure opens the air valve therein and the air flows through the passage 32 into the tubular chamber portion 20 and thence into 100

the tank above the liquid. If a source of pressure of the aforesaid character is not available, a hand pump may be applied with equal facility. The air under pressure is stored within container 10 and bears down upon the alcohol, lubricating oil or the like and forces the liquid 14 to enter the intake member 23 and flow upwardly through the conduit 21 into discharge 18, when the valve 17 is opened in the faucet or nozzle. A vessel such as a quart measure or the like placed upon the top of the container and immediately beneath the outlet of the faucet will receive the liquid discharged by pressure from the container when the faucet is opened. Sufficient pressure can be stored within the container to dispense substantially all the requirements therefrom during a day. Each day the air supply may be renewed as previously set forth.

20 The invention claimed is:

25 In a fixture for dispensing tanks, a bung fitting comprising an integral body having an enlarged bore extending inwardly from its bottom and an internally threaded tapered bore of reduced diameter at its top, means for securing the bottom of said body in said tank to communicate with the interior thereof, a discharge line threaded in said reduced bore, a flexible conduit extending loosely through said larger bore and tightly fitting within the inner end of said discharge line, and an air supply valve in said body communicating with said enlarged bore.

30 35 In witness whereof, I have hereunto affixed my signature.

DARWIN M. HESTON.
